CLAIM

The ornamental design for a protective headgear, as shown and described.

DESCRIPTION

FIG. 1 is a perspective view of a protective head gear showing our new design;

FIG. 2 is a top plan view thereof;

FIG. 3 is a side elevational view, the opposite side being a mirror image thereof;

FIG. 4 is a front elevational view thereof; and

FIG. 5 is a rear elevational view with the straps in extended position.
